Primary Examiner — Darlington Ly(74) *Attorney, Agent, or Firm* — Andrew C. Cheng**CLAIM**

The ornamental design for a tricycle, as shown and described.

DESCRIPTION

FIG. 1 is a front and left side perspective view of a tricycle embodying my new design;

FIG. 2 is a rear and left side perspective view thereof;

FIG. 3 is a front elevation view thereof;

FIG. 4 is a rear elevation view thereof;

FIG. 5 is a right side elevation view thereof;

FIG. 6 is a left side elevation view thereof;

FIG. 7 is a top plan view thereof;

FIG. 8 is a bottom plan view thereof;

FIG. 9 is a top, rear, and left side perspective view thereof, wherein the pedals are taken off and mounted onto the back of the frame;

FIG. 10 is a top, rear, and left side perspective view thereof, wherein the two rear wheels are closed together and the pedals are mounted onto the back of the frame; and,

FIG. 11 is an enlarged and partial perspective view of portion 11 of FIG. 1.
